RECEPTACLE AND CLOSURE MEANS
THEREFORFranz N. Merralls, Inglewood, Calif., assignor to
Rubbercraft Corporation of California, Ltd.,
Los Angeles, Calif., a corporation of California

Application February 5, 1946, Serial No. 645,515

1 Claim. (Cl. 150—3)

This invention relates generally to receptacle and closure means therefor, having particular application to tobacco pouches but adapted for utility in various types of containers by which an almost air-tight flexible seal between the opposed edges of the opening in such devices, or between any two members equipped with the elements thereof, may be effected.

Flexible containers composed of fabric, rubber, or various plastic equivalents are usually provided with metallic locking means such as slide fasteners or clasps, the latter requiring the inclusion of metal bars which line the mouth of the opening. Where flexibility is a feature of construction of such receptacles, the presence of the metallic locking elements, contributing a measure of rigidity to the assembly, is more or less objectionable. It is, accordingly, desirable for many applications to provide a sealing device which preserves to a maximum degree the flexibility of the assembly.

In some receptacles the security of the seal in withstanding extraordinary usage is of lesser importance than its effectiveness against the admission under normal conditions of air or liquid. For example, the proper storage of tobacco depends upon the preservation of humid atmospheric conditions. On the other hand, various sensitive instruments must be sealed against moisture when not in use in order to maintain their efficacy. The metallic structures of the prior art intended for analogous purposes cannot without exorbitant cost be adapted to effect a seal which will meet these requirements.

A principal object of the present invention is to provide a composite closure strip operable to extend the limited utility and obviate the above-mentioned and other disadvantages of prior art structures, comprising a pair of elongated flexible and compressible elements adapted to engage one another throughout their length and form a tight seal incident to their expansion upon such engagement.

More specifically an object is the provision of complementary strips embodying, respectively, a mortise, and a tenon contractible to permit its engagement in the mortise in response to lateral pressure thereagainst, any reach of the strip assembly being easily separable by the application of tension exerted upon either of the elements.

Another object is to provide a flexible bag or container having an elongated opening therein with the edges of the opening secured to the respective sealing strips, the latter being held in engagement with one another at each end of the

opening by the sides of the bag and the intermediate portions being engageable to form a substantially air-tight seal to thereby preserve prevailing conditions of humidity or dryness within the container.

Numerous other objects and advantages of my invention important in specific applications thereof, such for example as simplicity of construction, economy of manufacture, ease of operation, and efficacy of the seal, as well as neatness of appearance and conservation of the space required therefor in any container unit so equipped, will be apparent to those of skill in the art upon an examination of the following description read in the light of the accompanying drawings, in which:

Fig. 1 is a top edge view of a pouch or bag embodying my invention and illustrating the complementary parts of the sealing strip in engaged positions;

Fig. 2 is a view similar to Fig. 1, depicting the pouch open, i. e., with the elements of the seal displaced from one another intermediate their ends;

Fig. 3 is a side elevation of the pouch shown in Figs. 1 and 2; and

Fig. 4 is a sectional view taken on lines 4—4 of Fig. 1.

Referring to the drawings in detail, the numerals of which indicate similar parts throughout the several views, 5 designates generally a pouch or a sack for tobacco or the like formed of a single piece of fabric with the ends 6 sewed or otherwise secured together. The top of the sack is open, and to opposite edges of this opening the sealing elements of the present invention are secured by suitable means, as will be herein-after described more in detail. The pouch may include an inner imperforate lining of oil skin or any other material, but as this forms no part of the present invention, it is not illustrated or described. It will be understood that the sack or pouch 5 is merely illustrative of any of a plurality of containers or receptacles, composed of any material well known in the art and varying widely in size and design, to which the seal of my invention is applicable.

The sealing means of my invention comprises two elongated elements 7 and 8, preferably composed of rubber or other resilient and compressible material. The element 7 is generally rectangular in cross-section, having a smooth back surface 9 adapted for attachment by an adhesive or other well-known means to the edge 10 of one side of pouch 5 at the opening therein. The

3
upper and lower narrower surfaces 11 of the strip element 7 may also be smooth and, in the embodiment illustrated, perform no function.

The complementary sealing strip 8 adapted in operation to engage with strip 7 is also rectangular in cross-section but is more nearly flat, one surface 12 being secured to the opposite side 13 of pouch 5 adjacent the opening so that the narrower edges 14 of strip 8 are substantially flush with the corresponding surfaces 11 of strip 7. 10

The opposing surfaces 15 and 16 of the respective strips 7 and 8, respectively, are adapted to firmly engage one another, being secured in such relative positions when it is desired that the pouch be closed, in a manner about to be described. To this end, surface 15 of strip 7 is formed with a mortise groove 17 intermediate the edges thereof, having a narrow neck 18 displaced inwardly slightly from the plane of the sealing surface 15. The outer edges of groove 17 diverge from the reduced neck 18 as at 19 into the plane of sealing surface 15, the corners being preferably rounded as illustrated in Fig. 4. Groove 17 is enlarged at its bottom, forming an arcuate concavity 20 of a diameter greater than the width of neck 18 of the groove 17 so as to accommodate and retain therein a tenon 21 of corresponding shape. Tenon 21 is integrally formed with the middle of the opposing sealing surface 16 of the complementary strip 8, and conforms in cross-sectional contour with the shape of groove 17 but may be slightly larger for a purpose hereinafter described. With the sealing strips 7 and 8 secured to the edges of the mouth of the opening in pouch 5, tenon 21 is thus disposed directly opposite mortise groove 17.

As the sealing elements 7 and 8 are of a length equal to the length of the opening in the pouch of which they are a part, the corresponding ends of the strips are maintained in operative engagement by the converging sides of the container, i.e., the ends of tenon 21 are secured in the corresponding ends, respectively, of the mortise groove 17. Due to the flexibility of the material of which pouch 5 and sealing assembly are composed, the intermediate reaches of the sealing elements may be separated as indicated in Fig. 2 to permit access to the interior of the pouch.

When it is desired to close the pouch, the opening thereof is constricted, pressure being applied to the opposite edges of the mouth at a number of points along the length of the sealing assembly. In this manner tenon 21, which is at all times in transverse alignment with groove 17 in the complementary strip 7, is brought into contact with the latter strip and centered with groove 17 by the diverging outer edges 19 of the groove. Continued pressure compresses tenon 21 and, coincidentally, expands the neck 18 of groove 17 to permit the tenon to completely enter 60 into operative locking engagement therewith. Upon its reception in the concavity 20 of mortise groove 17, tenon 21 expands to firmly engage the bottom of the groove, and, correspondingly, the neck 18 of the groove is permitted to constrict 65 the reduced shank 22 of the tenon. Thus, an effective seal is provided not only between the

5
mortise 17 and tenon 21, but between the opposing sealing surfaces 15 and 16 of the respective strips 7 and 8, which are held firmly in engagement by reason of the association of the tenon in the mortise. The degree of pressure required to engage the sealing strips as well as the number of points along the length of the latter at which pressure must be applied will vary with the size and specific contour of the sealing strips, as well as with the resiliency of the material of which the same, and particularly the mortise and tenon elements thereof, are composed.

It will be understood that the assembly of the sealing expedients with the pouch as depicted in the drawings is only illustrative of one feature of my invention, and that any members, flexible or otherwise, equipped with the novel strips hereof may be effectively joined in a like manner. It is not essential that the ends of the sealing assembly be continuously engaged as hereinabove described, though it will be observed that, as in the embodiment illustrated, such arrangement permits the sealing of the fabric of the pouch with the ends of the strips so as to completely seal the container when the intermediate reaches of the strips are engaged. The cross-sectional contour of mortise groove 17 and tenon 21 may also be varied to meet specific requirements. Correspondingly, numerous changes in size, design, shape and number of the different parts may be made, and that all such variations will be within the scope of my invention as defined by the appended claim.

What I claim and desire to secure by Letters Patent is:

1. A device of the character described, a member having an elongated mortise groove therein formed with a restricted mouth in one surface thereof, a strip having a tenon projecting laterally from one surface thereof proportionate in size and of a shape identical with that of the groove and of a length corresponding to that of said groove, said tenon being composed of resilient, contractible material and normally slightly larger than said mortise groove so as to compel contraction of the tenon in order for its accommodation within said mortise groove, a flexible container having edges thereof forming a mouth, said edges overlying and being attached to surfaces of said member and strip, respectively, which are disposed at the opposite sides of the said member and strip from said mortise and tenon, respectively.
